UNITED STATES PATENT OFFICE.

SAMUELL O. HAYS, OF TRIPPLETT, MISSOURI.

COMBINED ROAD GRADER AND SCRAPER.

SPECIFICATION forming part of Letters Patent No. 694,963, dated March 11, 1902.

Application filed September 9, 1901. Serial No. 74,736. (No model.)

To all whom it may concern:

Be it known that I, SAMUELL O. HAYS, a citizen of the United States, residing at Triplett, in the county of Chariton and State of Missouri, have invented certain new and useful Improvements in a Combined Road Grader and Scraper, of which the following is a specification.

The objects of my invention are to provide a machine for this purpose of simple, durable, and inexpensive construction that when used as a grader may carry with it a comparatively large quantity of earth and may be readily moved laterally, so as to deposit the earth in depressions in the ground-surface that cannot be advantageously reached by wheel-graders.

A further object is to provide a device of the class that may be advantageously used as a road-scraper to accomplish all of the results of which an ordinary wheel-scraper is capable, and in addition thereto to provide a combined grader and scraper that may be turned around in a comparatively small space and that will leave the earth deposited by it when used as a grader in a smooth and regular manner.

A further object is to provide a device of this class that may be adapted for use in working ground-surface of different degrees of hardness—that is to say, in working very hard ground the pointed end of the scraper may be used partially as a plow and the scraper-blade extended at an acute angle relative to the line of advance, and when used in connection with ground that is less tightly packed the scraper may be extended at an angle more nearly approaching a right angle relative to the line of advance, so that a large amount of earth of this class may be handled.

My invention consists in certain details in the construction, arrangement, and combination of the various parts of the device, whereby the objects contemplated are attained, as hereinafter more fully set forth, pointed out in my claims, and illustrated in the accompanying drawings, in which—

Figure 1 shows top or plan view of the complete machine adapted for use as a road-scraper. Fig. 2 shows a vertical transverse sectional view, on an enlarged scale, through the indicated line 2 2 of Fig. 1. Fig. 3 shows in side elevation the caster-wheel for sup-

porting the rear end of the machine-frame, parts of the wheel-frame being broken away to show certain details of construction. Fig. 55 shows top or plan view of the caster.

Referring to the accompanying drawings, I have used the reference-numeral 10 to indicate the body portion of the machine. This body portion is preferably made of wood substantially oblong in transverse section, its major axis being in a vertical plane. Attached to the front lower edge of this body portion 10 is a scraper-blade 11, preferably curved forwardly a slight degree at its lower edge 65 and also dull at its lower edge. At one end of the part 10 is a metal point 12, sharpened at its lower edge.

The reference-numeral 13 indicates a supporting-beam fixed at one end to the end portion of the body 10 and extended at an acute angle relative to the said body portion. At its rear end is a swiveled caster-wheel frame 14, having a comparatively wide space between its arms. The caster-wheel 15 is pivoted between these arms, and both of its peripheral edges are beveled, so as to form a sharp edge at its periphery, and the said wheel 15 is of such dimension that a comparatively large space is left between the wheel 15 and the 80 arms 14. This construction prevents clogging of earth between the wheel and its supporting-frame and also prevents side movements or slipping of the wheel.

The numeral 16 indicates a brace connecting the end portions of the body 10 and the beam 13. On top of the central portion of the body portion 10 is an upright board 17 to prevent earth from passing through the top of the body portion. Fixed to the rear surface 90 of the body portion 10, near its free end, is a frame 18, having pivoted therein a block 19, designed to receive a bar 20, vertically adjustable therein by means of a set-screw 21 and curved upwardly and forwardly and then 95 downwardly and terminating some distance in advance of the body portion in a loop 22. This bar when not in use is swung to a position parallel with and to rest on top of the body portion 10, where it may be securely 100 held in position by means of the pin 23, which passes through the loop 22. Pivoted to the opposite end portion of the body 10 is a bar 24, connected therewith by a pin 25, so that

it may be detached, if desired. At the outer end of the bar 24 is a loop 26, and a chain 27 connects the loop 26 with the loop 22, and a chain 28 is attached to the loop 26 and is 5 also detachably connected with a whiffletree 29. At the pointed end portion of the body 10 a hook or staple 30 is provided in the front thereof, to which a chain 31 is attached, and this chain is also connected with the whiffletree 32. Near the other end of the body portion 10 is a hook or staple 33, similar to the staple 30, and for the purpose of attaching the chain 28 thereto when the device is used 10 as a grader.

15 Assuming that the device is to be used in the manner of an ordinary road-scraper, the parts are arranged as shown in Fig. 1, one or more draft-animals connected with the whiffletree 32, and one or more independent draft-20 animals being connected with the whiffletree 29. Then as the machine is advanced over the ground-surface it is obvious that the caster-wheel will support the body portion in position, and the blade will serve the same function as in an ordinary scraper, moving the earth to the rear end of the body portion and filling up the depressions in the ground-surface over which it passes. The independent team of draft-animals are preferably driven 25 abreast, and obviously when it is desired to pass around stumps or stones in the ground-surface they may be readily driven in such manner as to cause the machine to pass around such obstructions, and the scraper can 30 operate much closer to the stump or other obstruction than is possible in the ordinary wheel-scraper. Furthermore, assuming that it is desired to move the surface of the ground laterally to a considerable extent in one direction only the brace 24 and curved arm 20 are 35 dispensed with and the chain 28 is attached direct with the hook 33, or possibly it may be attached to the loop 22 of the arm 20. Then as the scraper is advanced over the ground-surface, going in the same direction, the ground is 40 thrown laterally a distance corresponding to the width of the path covered by the body portion of the machine. When the end is reached, the machine is partially turned 45 around, so that the end of the body portion to which the arm 20 is attached first engages the ground that had been piled up by the first operation of the scraper, and then the scraper-body is made to extend at such an angle that 50 the land will be moved laterally in the same direction as it was by the first movement of the scraper. This is done by simply adjusting the lengths of the chains 28 and 31 or by permitting one of the independent teams of 55 draft-animals to advance some distance in the rear of the other team. This result has been found in many instances to be highly 60 advantageous and obviously cannot be accomplished by the use of the ordinary wheel-scraper.

65 When it is desired to use the device as a grader, the arm 20 and the brace 24 are either

dispensed with or may rest on top of the body portion 10, and the chains 28 and 31 are hooked direct to the hooks or staples 33 and 30, and the draft-animals are then abreast of each other, so that the body portion stands at right angles to the line of advance. Obviously the ground-surface is carried with the grader as it is advanced, and a considerable quantity may be thus carried, because of the board 17 at the top of the body portion and, further, because the chains serve, to a certain extent, to prevent the ground from moving laterally past the ends of the body portion. When it is desired to dump the grader, the operator simply grasps the handle at the rear end of the arm 13 and elevates same, whereupon the entire machine tilts over forwardly and the ground is dumped and at the same time is smoothed by the body portion. Another material advantage that may be attained by the use of my machine is that it may be turned around in a very small space by simply unhitching one 85 of the teams of draft-animals and permitting the other to drag the machine back to its starting position. Furthermore, in carrying the ground to dump it over an embankment my machine is especially advantageous, because the draft-animals may be advanced 90 direct toward the bank and then separated and the teams driven in opposite directions, thus bringing the scraper with its load of earth close to the edge of the bank, whereupon the operator may dump the ground over the bank. Then one team may be unhitched and the other permitted to drag the machine back to its starting-point. Furthermore, when the device is in use either as a 95 grader or scraper the operator may readily move it laterally to a degree required for avoiding obstructions or for dumping part or all of the ground carried by the machine into the depressions of the ground-surface over 100 which the draft-animals themselves could not pass and which therefore could not be reached by the use of the ordinary wheel-scraper.

Having thus described my invention, what I claim, and desire to secure by Letters Patent 115 of the United States therefore is—

1. An improved road grader and scraper comprising a straight body portion to engage the ground-surface, means for attaching independent teams of draft-animals to the opposite end portions of the body, said means for attaching being adjustable as to length so that the teams may advance abreast and either end of the body portion stand in the rear of the other end or so that the body portion may stand at right angles to the line of advance, a bar projecting rearwardly from the body portion and a caster-wheel swiveled in said bar, for the purposes stated.

2. An improved combined road grader and scraper comprising in combination a body portion having a sharp metallic point at one end and a metal blade at its front edge, a bar projecting rearwardly therefrom, a caster-wheel

swiveled to the rear end of said bar, means for attaching a team of draft-animals to the end of the body carrying the pointed projection, a brace 24 pivoted to the body portion 5 near the end having the pointed projection and projecting at an acute angle from the body portion, a chain or its equivalent attached to the said brace, and a whiffletree connected therein, and means for connecting the 10 outer end of the brace with the other end of the body portion, for the purposes stated.

3. An improved combined road grader and scraper, comprising in combination a body portion, a metal blade fixed to the lower forward edge thereof, a sharp metal point at one end of the body portion, a bar fixed to the end of the body portion having the sharpened point and projecting rearwardly at an acute angle relative to the body portion and having 15 a handle at its rear end, a caster-wheel swiveled in the rear end portion of the said bar, a bar connecting the rear end of the said bar and the body portion, hooks and staples fixed to the front face of the body portion 20

near its opposite ends a bracket fixed to the rear face of the body portion at the end opposite from the pointed projection, an arm swiveled in said bracket and projecting upwardly over the body portion and in front of it, a brace pivoted to the body portion near 25 its pointed end and projecting forwardly from the body portion at an acute angle relative thereto, means for detachably connecting the outer end of said brace with the said arm, a chain or the like adjustable as to length and 30 detachably connected with the hook or staple near the pointed end of the body portion and having a whiffletree connected therewith, a chain or the like adjustable as to length and 35 detachably connected with the said brace and having a whiffletree connected therewith, arranged and combined in the manner set forth 40 and for the purposes stated.
